CLAIM

The ornamental design for a needle resheather, as shown and described.

DESCRIPTION

FIG. 1 is a front perspective view of a needle resheather, showing our new design;

FIG. 2 is a front elevational view thereof;

FIG. 3 is a top plan view thereof;

FIG. 4 is a left side elevational view thereof; and

FIG. 5 is a right side elevational view thereof.

The bottom and rear are plain and flat.
